UNITED STATES PATENT OFFICE.

JOHN DEWRANCE, OF SOUTHWARK, ENGLAND.

WATER-LEVEL INDICATOR.

SPECIFICATION forming part of Letters Patent No. 727,599, dated May 12, 1903.

Application filed August 2, 1901. Serial No. 70,657. (No model.)

To all whom it may concern:

Be it known that I, JOHN DEWRANCE, a subject of the King of Great Britain and Ireland, residing at 165 Great Doverstreet, Southwark, in the county of Surrey, England, have invented new and useful Improvements in Water-Level Indicators, (in respect whereof I have applied for a patent in Great Britain, to bear date February 5, 1901, No. 2,517,) of which the following is a specification.

This invention relates to an improved method of constructing and working water-gages provided with automatic valves, with the object of effecting a "blow-off" through the upper arm and gage-glass and through the lower arm, respectively, at successive stages in the complete operation of a mechanical appliance specially designed for the purpose.

Water-gages as commonly constructed comprise two arms adapted for attachment to the boiler-front and furnished with cocks, whereby the steam and water, respectively, may when necessary be shut off. Between the two arms a gage-glass is mounted, and the lower arm is in addition provided with a blow-through cock. When it is desired to provide against the escape of steam or water in the event of the gage-glass bursting or being broken, each arm is usually furnished with a ball-valve, which under normal conditions is off its seat, but which upon fracture of the gage-glass instantly seats itself and intercepts the escape of the steam or other fluid under pressure. When using a water-gage of this description, it is necessary when blowing through the upper arm and gage-glass not simply to close the cock in the lower arm and open the blow-through cock, but to adopt some means for preventing the ball-valve at the upper end of the gage-glass seating or for displacing it if seated.

It may be remarked that in order to insure that the level of the water shown in the gage-glass corresponds with that in the boiler it is essential that the passages through the upper and lower arms should both be quite clear. Opening the blow-through cocks is not by itself sufficient to determine that the gage is in proper working order. It is necessary to open the blow-through cock first with one passage open and the other closed and then with

the latter open and the former closed. Mechanism has been applied to the shut-off cocks for systematically accomplishing these operations; but it is undesirable that the shut-off cocks should be interfered with; and my invention is accordingly designed to accomplish the objects in view by suitably manipulating the automatic valves and the blow-through cock without interfering with the upper and lower shut-off cocks, both of which remain constantly open.

In the accompanying drawings, Figure 1 is a vertical section of a water-level indicator constructed according to my improved method and wherein the automatic shut-off valves may be alternately unseated, so as to enable a blow-off to be effected through the lower and upper arms consecutively by the movement of a single handle. Fig. 2 is a corresponding elevation. Figs. 3 and 4 are horizontal sections through the upper and lower arms, respectively. Fig. 5 is a section taken on the line *x* *x* in Fig. 1.

The mechanism illustrated by way of example and adapted for working or controlling the automatic valves in order to accomplish the objects above described comprises a vertical spindle A, which passes through the respective (upper and lower) valve-chambers B and B' and has mounted upon it bodies C and C', pertaining, respectively, to the upper and lower valves. The body C carries projections or fingers *c c*, while the body C' carries projections or fingers *c' c'*, adapted in each instance to act both as strikers to unseat the automatic valves *b b'* and as guards to prevent their regaining their seats otherwise than when the particular stage reached requires that one or the other or both of them should do so. The bodies C and C' are each formed with an inclined surface *c⁰ c^x*, whereon the valve *b* or *b'* rests or travels to or from its seating. The spindle A may extend to a point within convenient reach of the attendant and be fitted at A' with a hand-wheel. Upon a rotative movement, preferably a complete revolution, being imparted to the spindle A the automatic valves *b b'*, controlling the upper and lower arms, as also the blow-through cock, are successively operated in such a manner as to bring about, first, a

blow through the one arm, subsequently a blow through the other arm, and ultimately to leave the apparatus in its normal working condition, so that the automatic valves are 5 in a position to shut off the water and steam in the event of the gage-glass breaking.

The operation is as follows: In the drawings the parts are shown in their normal working positions. Assuming it is desired to effect a 10 blow-through, the spindle A is turned, say, in the direction of the arrow, Fig. 1, through an angle of ninety degrees. This movement has the effect of opening the valve b' , owing to the openings c^2 and c^3 being brought into 15 alinement with the passage b^x in the valve-chamber B', the ball b' being held off its seating by the fingers c' . At the same time the valve b is allowed to seat, owing to the openings c^4 and c^5 coming into alinement with the 20 passage b^0 in the valve-chamber B, the ball b entering the opening c^4 and by means of the steam-pressure closing the passage d to the gage-glass D. Thus the equilibrium in the latter is disturbed, resulting in a blow through 25 the lower arm.

E is the blow-off cock, and F a nozzle adapted for the reception of a waste-pipe. By turning the spindle A through a further angle of ninety degrees both the valves b and b' 30 will be opened, or, in other words, equilibrium will be restored. A similar degree of rotation of the spindle A, however, in the same direction has the effect of bringing the openings c^2 c^3 again in alinement with the 35 passage b^x ; but the valve b' is now forced into the opening c^3 against its seating, thereby cutting off or closing the passage d' to the gage-glass D. The equilibrium is thus again disturbed and a blow through the upper arm 40 effected. Upon imparting another quarter of a revolution to the spindle A the valves b b' are returned to their normal working positions, in which they are capable of shutting off the water and steam should the gage-glass 45 break. G G' are the usual shut-off cocks applied, respectively, to the upper and lower arms.

If the apparatus be inverted, what has been

referred to as the lower arm becomes the upper arm, and vice versa.

What I claim as my invention, and desire to secure by Letters Patent, is—

1. In a water-level indicator, for steam-generators and the like, provided with automatic valves, the herein-described means for enabling a "blow-off" to be effected through the lower and upper arms consecutively as the result of a complete rotative movement and without interfering with the shut-off valves, such means comprising a spindle arranged to 60 traverse the upper and lower arm passages, automatic valves respectively located in the said passages, and bars or projections formed in or upon the said spindle at its points of intersection with the passages, the said bars or 65 projections being suitably shaped to unseat or to prevent the seating of the automatic valves inclosed within them, substantially as herein described.

2. The herein-described means for working 70 or controlling the automatic valves of water-level indicators for steam-generators and the like comprising upper and lower ball-valves, chambers for said valves, a vertical spindle which passes through the lower and upper 75 valve-chambers and has mounted thereon bodies carrying projections or fingers adapted to serve both as strikers to unseat the valves and as guards to prevent them regaining their seats excepting when the conditions require 80 they should do so, substantially as set forth.

3. For working or controlling the automatic valves of water-level indicators for steam-generators and the like, a spindle A having bodies C C' mounted thereon which receive 85 the ball-valves, the said bodies carrying projections or fingers c c' and having formed therein inclined surfaces c^0 c^x , substantially as and for the purposes specified.

In testimony whereof I have signed my 90 name to this specification in the presence of two subscribing witnesses.

JOHN DEWRANCE.
